(57) CLAIM

The ornamental design for a shoe, as shown and described.

DESCRIPTION

FIG. 1 is a top lateral perspective view of a shoe showing my new design;

FIG. 2 is a top view of the shoe thereof;

FIG. 3 is a medial side view of the shoe thereof;

FIG. 4 is a lateral side view of the shoe thereof;

FIG. 5 is a front view of the shoe thereof;

FIG. 6 is a rear view of the shoe thereof; and,

FIG. 7 is a bottom view of the shoe thereof.

In FIGS. 1-7, the lighter wider spaced broken lines depict portions of the shoe that form no part of the claimed design. The bold broken lines depict stitching, which does form a part of the claimed design.

1 Claim, 6 Drawing Sheets(56)
